ORE REDUCTION MILL

George Foye Ainsa, San Francisco, Calif., assignor
of one-third to Dolores C. Ainsa and one-third
to Eugene de Reynier, Berkeley, Calif.

Application April 11, 1938, Serial No. 201,232

3 Claims. (Cl. 83—46)

The present invention relates generally to a reducing mill of the type in which an agglomerate of loose lumpy material is reduced or pulverized by impact of the larger particles of agglomerate against a stationary impact receiving surface, and more particularly to a reducing mill, wherein the impact action is produced by a centrifugally operating agglomerate throwing member.

An object of the present invention is to provide a reducing mill for reducing and pulverizing an agglomerate, such as metal bearing ores, coal, limestone, and other like substances.

Another object of the present invention is to provide a reducing mill for the reduction of coarse and lumpy agglomerate, wherein the reducing action is produced by centrifugally throwing the agglomerate against a relatively stationary surface where the agglomerate will be reduced by impact against said surface.

Another object of the present invention is to provide a reducing mill for the reduction of coarse and lumpy agglomerate, wherein the unreduced agglomerate is thrown by centrifugal force against a relatively stationary mass of agglomerate to reduce the agglomerate by the impact between the centrifugally thrown and stationary agglomerate.

Another object of the invention is to provide a reducing mill having the above characteristics, wherein the unreduced agglomerate will be recirculated through the mill in a continuous manner until reduced to a required fineness.

Another object of the present invention is to provide an agglomerate reducing mill acting upon the centrifugal principle, wherein a circulation of air is relied upon to separate and withdraw the reduced agglomerate from the mill when it has been reduced to the proper fineness.

Another object of the present invention is to provide a reducing mill of a character similar in many respects to that described in my copending application for Letters Patent, Serial No. 14,012, filed April 1, 1935, and now Patent No. 2,171,526, entitled Reduction mill.

In the art to which the present invention relates, there has been devised a large number of mills for reducing agglomerate, wherein opposing masses of agglomerate are held by centrifugal force and caused to rub against each other, so as to obtain a reducing action by friction against opposing masses of agglomerate. In reducing mills of this character the agglomerate is reduced slowly by a rubbing action which takes place between the relatively moving particles of

the agglomerate as these particles travel under the influence of centrifugal force and pass out of the mill at the periphery of centrifugally operating and opposed rotor elements. Such reducing mills require an excessive pressure between the particles, and consequently a large amount of power is necessary to operate the mill.

As distinguished from the prior art mills, the present invention contemplates a free throwing of the agglomerate by centrifugal force from a suitable rotor element and against a stationary impact receiving surface, where the agglomerate will be reduced by impact.

For a better understanding of the invention and its mode of operation, reference should be had to the accompanying drawings, wherein there is shown by way of illustration and not of limitation, a preferred embodiment thereof.

In the drawings, wherein like numerals designate like parts throughout the several views;

Figure 1 is a vertical side view of a mill, with parts in section, to disclose the interior construction thereof.

Figure 2 is a plan view along line II—II of the mill illustrated in Figure 1, also having parts broken away and in section, so as to reveal details of construction.

Figure 3 is an end view of the mill taken along line III—III of Figure 1, looking in direction of arrows, and

Figure 4 is a similar view taken along line IV—IV of Figure 1, looking in direction of arrows.

In Figure 1 of the drawings there is illustrated in its entirety a mill constructed in accordance with this invention, which is particularly adapted to the reduction of loose and lumpy material, such as metal bearing ores, cement, rock, clay and the like. As here shown, the various elements of the mill are mounted in cooperating relation upon a suitable structural iron frame 10 having a pedestal 11 at one end, upon which there is journaled a centrifugal rotor element 12, and at the other end of the frame 10 there is a suitable platform arrangement 13 to facilitate the feeding of the material to be reduced to the mill, as will hereinafter appear. The centrifugal agglomerate throwing rotor element 12 is carried by a horizontally disposed shaft 14 which is journaled in a bearing 15 and driven through a belt 16 by an electric motor 17. Between the pedestal 11 and the platform 13 the frame 10 is adapted to support a rotatable drum-like housing, which is here designated generally by the numeral 18. This housing 18 is provided at its ends with rails 19 and 20 that engage and

ride upon spaced supporting rollers 21 and 22 in a manner well understood in the art. At the outer end of the rotatable housing 18 there is an annular driving rack 23, which in cooperation with a spur gear 24 upon the end of the shaft of a motor 25 is adapted to provide a driving means therefor. Arranged adjacent the other side of the rotatable housing 18 there is an arch-like stationary agglomerate intercepting member 26 which is disposed over and around the open end of the centrifugal rotor element 12 and against which the agglomerate thrown by centrifugal force from the centrifugal rotor element 12 will strike. This stationary agglomerate intercepting member 26, which is shown in the form of an arch that bridges over the open end of the rotor element 12 may be of solid construction, but is preferably of open construction, so that it will accumulate and retain a mass of agglomerate 27 in a position where the agglomerate will provide a constantly renewing surface against which the centrifugally thrown agglomerate will strike. As a result of this construction it will be seen that both the accumulated agglomerate 27 retained by the member 26 and the thrown agglomerate will be subject to reduction by impaction, and as a result the efficiency of the mill will be greatly increased and at the same time the necessity for replacing worn parts, such as is required in mills having metallic grinding surfaces, will be reduced to a minimum, and further, a contamination of the reduced agglomerate by metal worn from the mill parts will be eliminated.

As illustrated, the stationary member 26 is of hollow rectangular cross-section and is provided with an open annular area 28 around its inner wall through which the agglomerate 27 may be initially projected from the centrifugal rotor element 12 to build up an impact receiving surface of the agglomerate 27. It will be understood as the agglomerate thrown from the centrifugal rotor element 12 is acted upon, the unreduced particles will flow down by gravity over an inclined chute 29 properly positioned at the lower part of the stationary member 26, where it will be discharged into the rotatable drum-like housing 18. In order to insure a discharge of the unreduced agglomerate to the rotatable housing 18 the stationary agglomerate intercepting member 26 is provided with an outwardly extending discharge directing flange 30 which projects through an opening 31 in the adjacent wall of the rotatable housing 18. Disposed substantially centrally of the rotatable housing 18 and opposite the open end of the centrifugal rotor member 12 there is a fixed baffle 32 upon the inside surface of which there is provided a shock absorbing facing 33 of rubber or like material. This baffle 32 serves to prevent a direct discharge of any of the unreduced agglomerate from the centrifugal rotor element 12 into the rotatable housing 18, except at a point near the bottom of the rotatable housing 18, where the unreduced particles will be discharged by gravity into the rotatable housing 18. At this point it will be noted that the flange 30 is inclined downwardly so as to permit this discharge of the agglomerate into the rotatable housing 18.

Arranged in spaced relation throughout the inner periphery of the rotatable housing 18 there is a plurality of buckets 34 which are inclined so as to pick up and carry the agglomerate discharged therein to a point corresponding to their uppermost point of travel, where the ag-

glomerate carried by the individual buckets 34 will be discharged into a stationary hopper 35 which, as shown, has its agglomerate receiving end 36 disposed beneath the buckets 34 within the rotatable housing 18 and its agglomerate discharging end 37 disposed so as to direct the returned agglomerate to a point near the outer periphery of the centrifugal rotor element 12 where, due to the high linear speed of the rotor element at this point, the agglomerate will be subjected to intense frictional heat, which in the case of sulphite bearing ores will result in a burning of these impurities as well as in a reduction of the ore by impaction as it is thrown against the impact receiving surface of agglomerate 27 formed, as described above, upon the stationary agglomerate intercepting member 26. An additional feature of the stationary hopper 35 is that one of its sides, designated by the numeral 38, is carried upwardly in a direction substantially tangent to the axis of the centrifugal rotor element 12, where it will recapture any agglomerate which may rebound within the centrifugal rotor and which is not thrown out against the surface of agglomerate 27 by centrifugal force by the rotor element 12.

For the purpose of introducing agglomerate into the mill constructed as above described, the rotatable housing 18 is provided with a centrally disposed stationary end closure plate 39 which is carried by the frame 16, and extending through this end closure plate 39 there is a stationary chute 40 having a hopper-like agglomerate receiving end 41, and positioned below and partially around the chute 40 the end closure plate 39 has a semiannular manifold 42 from which a suction conduit 43 extends. In operation the suction conduit 43 will be connected to a suitable suction type blower which will create a circulation of air through the mill to carry away all agglomerate which is reduced to a proper fineness. In order to limit the discharge of agglomerate to a particular fineness, the intake opening of the manifold 42 may be provided with a screen 44 of suitable mesh. When suction is produced upon the outlet pipe 43, air will be drawn into the mill, in the main, through an opening 45 which is provided at the rear of the centrifugal rotor member 12. Air will also find admission into the mill in the clearance space 46 between the wall of the rotatable housing 18 and the flange 31 carried by the stationary agglomerate intercepting member 26. The intake of air at these points will also serve to prevent the escape of any reduced agglomerate from the mill in the form of dust, and as a result no precaution to avoid such an escape at these points will be necessary. In order to maintain this suction and prevent any short circuiting of the air flow, as described above, by the inlet of air through the chute 40, this chute is provided with opposed damper-like elements 47 which are biased into a closed position by weighted ends 48. When agglomerate is to be introduced into the mill it will first be deposited in the hopper-like end 41 of the chute 40 and then the damper-like elements 47 will be opened to permit a discharge of the agglomerate into the mill, after which the damper-like elements 47 will be permitted to again close.

When the mill, constructed as described above, is in operation, it will be seen that the agglomerate may be deposited in the hopper 41 and discharged through the chute 40 by an opening 75 of the damper-like elements 47. This will permit

the agglomerate to fall down into the bottom of the rotatable housing 18 where the buckets 34 carried thereby will pick it up and discharge the agglomerate into the hopper 36 at the upper end of the chute 35. From this point the agglomerate will be discharged from the lower end 37 of the chute 35 against the interior surface of the centrifugal rotor element 12, where, as illustrated, a layer of agglomerate 49 will be retained by centrifugal force. At this point it should be noted that the centrifugal rotor 12 is provided with a wear resisting ring 50 that projects inwardly a slight distance about its rim. When the rotor 12 is in operation this ring 50 serves to entrap sufficient of the agglomerate to produce a protective layer of the agglomerate within the rotor 12 and reduces the wear upon the rotor 12 to a minimum. When the agglomerate thus introduced strikes the agglomerate 49 carried by the rotor element 12, excessive frictional heat will be created which will serve to burn out any volatile substances carried by the ore, as for example, sulphites and the like. As the rotatable element 12 rotates it will also carry the major portion of the agglomerate discharged thereupon around by centrifugal force and discharge it centrifugally against the impact surface 27 which is provided by the accumulation of agglomerate in the stationary member 26. After the agglomerate has been thus thrown against the stationary agglomerate surface 27, the unreduced particles will fall down by gravity into the bottom of the stationary member 26 where it will now flow by gravity over the lip 30 and into the lower part of the rotatable housing 18. This unreduced agglomerate will then be again picked up by the buckets 34 and return to the hopper 36 at the upper end of the chute 35 for a repetition of the above reduction cycle.

During the above operation it will be assumed that the suction blower connected to the outlet conduit 43 is operating, and as a result the finely reduced agglomerate will be picked up by the circulation of air passing through the openings 45 and 46 of the mill and carried out through the outlet conduit 43 for further treatment.

While I have, for the sake of clearness and in order to disclose my invention so that the same can be readily understood, described and illustrated a specific device and arrangement of parts, I desire to have it understood that this invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is—

1. In a reduction mill of the character described, the combination of a bowl-like centrifugally operating agglomerate receiving member disposed to rotate about a horizontal axis and having a single open end disposed in a vertical plane, a stationary agglomerate intercepting member disposed outwardly in spaced relation and in the plane of the open end of said centrifugally operating bowl-like member, said stationary agglomerate intercepting member being in the form of a hollow arch forming a cavity that bridges over and extends downwardly along each side of said bowl-like member and terminates in a chute-like discharge outlet, a rotatable drum-like housing disposed adjacent said sta-

5 tionary agglomerate intercepting member adapted to receive agglomerate as it falls from said member, an agglomerate directing chute for directing agglomerate into said centrifugally operating bowl-like member when in rotation, and a plurality of pockets arranged upon the inner peripheral surface of said rotatable drum-like housing adapted to return the agglomerate collected by said drum-like housing back to said chute, whereby the unreduced agglomerate thrown from said bowl-like member and discharged from said agglomerate intercepting member will be recirculated to said centrifugally operating bowl-like member until it is reduced to a desired fineness.

2. In a reduction mill of the character described, the combination of a bowl-like centrifugally operating agglomerate receiving member disposed to rotate about a horizontal axis and having a single open end disposed in a vertical plane, a stationary agglomerate intercepting member disposed outwardly in spaced relation and in the plane of the open end of said centrifugally operating bowl-like member, said stationary agglomerate intercepting member being in the form of a hollow arch that bridges over and extends downwardly along each side of said bowl-like member and terminates in a chute-like discharge outlet, a rotatable drum-like housing disposed adjacent said stationary agglomerate intercepting member adapted to receive agglomerate as it falls from said member, an agglomerate directing chute for directing agglomerate into said centrifugally operating bowl-like member when in rotation, a plurality of pockets arranged upon the inner peripheral surface of said rotatable drum-like housing adapted to return the received agglomerate back to said chute, whereby the unreduced agglomerate discharged from said agglomerate intercepting member will be recirculated to said centrifugally operating bowl-like member until it is reduced to a desired fineness, and a second agglomerate introducing chute extending into said rotatable drum-like housing through which the agglomerate is initially introduced into the mill.

3. In a reduction mill of the character described, the combination of a horizontally disposed bowl-like element adapted to be rotated at a high speed about a horizontal axis with its open end disposed in a vertical plane, means for continuously feeding agglomerate into the open end of said rotatable bowl-like element, whereby said introduced agglomerate will be continuously thrown by centrifugal force through the open end of said bowl-like element, a stationary thrown agglomerate intercepting member disposed in a vertical plane and extending over and around the open end of said bowl-like element having an open box-like portion adapted to temporarily retain a part of the agglomerate thrown out by centrifugal force from said bowl-like element, whereby the agglomerate thrown from said rotatable element will impact against a continually renewing impact receiving surface of the agglomerate temporarily retained in the open box-like portion of said stationary impact receiving member during the operation of the mill, and a discharge outlet leading from said agglomerate intercepting member to said continuously feeding means, whereby the thrown and temporarily retained agglomerate will be subjected to further reducing action.
